UNITED STATES PATENT OFFICE.

JOHN A. FENTON, OF NORTH ANDOVER, MASSACHUSETTS.

STOP-MOTION.

1,353,226.

Specification of Letters Patent. Patented Sept. 21, 1920.

Application filed January 15, 1920. Serial No. 351,727.

To whom it may concern:

Be it known that I, JOHN A. FENTON, a citizen of the United States, residing at North Andover, in the county of Essex and 5 State of Massachusetts, have invented a new and useful Stop-Motion, of which the following is a specification.

This invention relates to new and useful improvements in stop motion mechanisms 10 for twisting or spinning frames, and it is the primary object of the invention to provide a device for automatically throwing the thread feeding rollers out of operation when the thread operating over the rollers has become broken, thus eliminating any possibility of the thread becoming snarled or 15 tangled.

A further object of the invention is to provide means controlled by the tension of 20 the thread passing through the frame, for accomplishing the operation of the stop motion.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawings:—

35 Figure 1 illustrates a longitudinal sectional view through the feeding rolls constructed in accordance with the present invention;

40 Fig. 2 illustrates a side elevational view of the roll supporting bearings; and

Fig. 3 illustrates a rear elevational view 45 of the thread feeding roll.

Referring to the drawings in detail, the reference character 5 designates the base 45 of the frame which may be constructed of any suitable material and the dimensions according to the size of the frame to be supported thereon.

The spaced bearings 6 are supported on 50 the base 5, and extend upwardly therefrom, the bearings 6 being shown as comprising slotted arms, the slotted portion being indicated at 7, and extends from the upper end of the respective arms terminating at a point 55 adjacent the base 5.

As before stated these arms are supported

in spaced relation with each other to support the thread feeding rollers 8 and 9, and the power roller 10, each of the rollers being provided with laterally extending shafts 11, 60 which shafts are of a diameter equal to the width of the slotted portions 7 to permit free rotary movement of the thread feeding rollers and power roller, but at the same time restrict movement thereof. 65

The power roller 10 has connection with any suitable power device to cause the rotation of the power roller, and is provided with the gear 12 on one end thereof, which gear 12 is in mesh with the gear 13 provided on the lower thread feeding roller 9, so that movement of the power roller 10 transmits rotary motion to the thread roller 9 through the gears 12 and 13. 70

The upper thread feeding roller 8 has 75 its periphery contacting with the periphery of the thread feeding roller 9 so that rotary movement of the roller 9 is imparted to the roller 8 to cause the thread 14, which is shown as looped around the roller 8, to be 80 fed between the rollers 8 and 9 to the twisting machine. It is therefore obvious that the weight of the upper roller 8 causes the same to contact with the roller 9 at all times. 85

At the forward end of the base 5 is provided a supporting standard 15, which has its upper portion cut away as at 16 to provide a clearance for the thread guide 17, which end is also apertured and embraces the shaft 18 to permit the thread guide 17 90 to oscillate with relation to the standard 15.

This thread guide 17 includes the laterally extending arms 19 and 20, the arms 19 being provided with a roller 21, having the flanges 22 formed on opposite ends thereof, the flanges 22 providing a guide way for the thread 14 operating under the roller 21, for preventing lateral movement of the thread, and to insure the thread being held in a proper feeding relation with the feeding 100 rollers 8 and 9. 95

Formed substantially intermediate the length of the power roller 10, is a cut out portion 23, which cut out portion provides a guide for the strap 24 forming a part of 105 the operating mechanism, the forward end of said strap 24 having connection with the thread guide 17 through the link 25 which passes through an opening 26 formed in the thread guide, the opposite end of said strap 110 24 having connection with the weight 27, whereby the strap 24 is caused to move in

one direction, when the thread guide is freed to move toward the thread feeding rollers 8 and 9.

Supported on the strap 24 at a point in 5 front of the rollers 8 and 10, is a wedge shaped block 28, which block is normally held in a position out of contact with the rollers 9 and 10, by the tensions of the thread 14 passing over the thread guide 17, 10 the thread 14 as before stated operates under the roller 22 and over the rod 29 which is a part of the arm 20 of the thread guide.

In view of the fact that the rod 29 is 15 smaller in diameter than the roller 22, it will be seen that the thread 14 is under tension when the same is passing through the thread guide 17, which tension causes the thread guide 17 to pivot forwardly.

The block 28 is now held out of contact 20 with the rollers 9 and 10, but if the thread 14 becomes broken due to the same being caught in the machine, the weight 27 will fall by gravity to a position in close proximity with the base 5, whereupon the wedge 25 shaped block 28 moves between the rollers 9 and 10 with the result that the rollers 3 and 9 are lifted until the gears 12 and 13 are out of mesh. It is therefore obvious 30 that rotation of the power roller 10 does not affect the thread feeding rollers 8 and 9, with the result that the rollers 8 and 9 are held stationary and no longer feed the thread through the machine associated with the device.

35 In view of the foregoing it is believed that a detail description of the operation of the device, is unnecessary.

Having thus described the invention, what is claimed as new is:—

40 1. A stop motion mechanism comprising in combination, thread feeding rollers, a power roller supported under the thread feeding roller, bearings for supporting the rollers, said power roller having a groove 45 formed therein, a pivoted thread guide over which the thread passes, a strap having connection with the thread guide, a weight on

the opposite end of the strap, a wedge shaped block supported by the strap and adapted to move between the power roller 50 and thread feeding rollers, for throwing the rollers out of operation, and said thread guide adapted to exert a tension on the strap for normally holding the block out of 55 operation.

2. A stop motion mechanism comprising in combination, thread feeding rolls, a power roller supported under the thread feeding rolls, a pivoted thread guide operating in proximity to the rollers, the 60 power roller having a groove formed in the periphery thereof, a flexible member operating between the rollers and carrying means moving in the groove, a weight carried at one end of the flexible member, means 65 associated with the thread guide for normally holding the first mentioned means out of contact with the rollers, and said weight adapted to move the first mentioned means between the rollers to cause the rollers to 70 become disengaged.

3. A stop motion mechanism comprising in combination, thread guiding rollers, a power roller disposed under the thread guiding rollers, a flexible member operating between predetermined rollers, a wedge shaped member carried by the flexible member, the power roller having means to accommodate the flexible member to prevent lateral movement thereof, a weight on one end of the flexible member for carrying the wedge shaped member over the power roller for disengaging the rollers and power roller, and means for normally holding the wedge 80 shaped member out of contact with the power roller.

In testimony that I claim the foregoing as my own, I have hereto affixed my signature in the presence of two witnesses.

MR. JOHN A. FENTON.
